CURTAIN ROD END MEMBER WITH INTERIOR SHEAVES

Filed August 6, 1925

2 Sheets-Sheet 2

UNITED STATES PATENT OFFICE.

CHARLES W. KIRSCH, OF STURGIS, MICHIGAN.

CURTAIN-ROD END MEMBER WITH INTERIOR SHEAVES.

Application filed August 6, 1925. Serial No. 48,486.

This invention relates to curtain and drapery fixtures and particularly to that type of said devices adapted for the so-called "pull-string" type of curtains or draperies, 5 the meeting edge portions of which are adapted to be brought together to close a passage-way or exclude or dim light from windows, etc. and separated for opposite reasons and are operable by means of a cord 10 having its end portions disposed at one side of a window-casing or the like.

The present invention relates more particularly to the type of curtain rods which are mounted at the tops of window-casings 15 and have their main or middle portions spaced from the said casing and has for its object to provide means whereby the operating cord for the curtains or drapes is disposed mainly within the rod with only its 20 end portions disclosed to view at one side of the window-casing.

The type of curtain rod to which the invention most directly relates is the hollow or tubular, longitudinally slotted type which 25 comprises a straight main or middle portion adapted to extend parallel with the window-casing and is supported by means of L-shaped end portions telescopically associated therewith. This type of rod is exemplified 30 in Letters Patent No. 1,250,190, dated Dec. 18, 1917, and the present invention relates particularly to the end members of this type of rods having for its particular object 35 to provide means for incorporating into either arm of each end member and mounting in one arm thereof, sheaves over which the operating cord for drapes of the type mentioned is trained.

The preferred embodiment of the invention 40 is illustrated in the accompanying drawings wherein:—

Fig. 1 is a plan view, partly in section, of 45 a curtain rod constructed in accordance with the invention.

Fig. 2 is a vertical section of the same on the line 2—2 of Fig. 1.

Figs. 3 and 4 are fragmentary plan sections of the same on the lines 3—3 and 4—4, respectively, of Fig. 2.

Fig. 5 is a sectional view of the same on the line 5—5 of Fig. 1.

Fig. 6 is a perspective view of one of the end members of the rod.

Fig. 7 is a transverse section on the line 55 7—7 of Fig. 5.

Fig. 8 is a section on the line 8—8 of Fig. 5.

Fig. 9 is a perspective view of a drapery carrier disassociated with the rod.

The curtain rod into which the present invention is shown to be incorporated in this instance comprises a straight section 1 of the conventional hollow flat rod, C-shaped in cross section, having a continuous slot in its rear face which is bordered by flanges 2 upon which suitable drapery carriers 3 are slidably mounted. An exemplary type of carrier 3 is shown in Fig. 9, the same comprising a metal plate equipped with flanges 4 each having recesses 5 to receive the flanges 2 of the rod, the plate being also provided with a slot 6 and projection 7 for attaching a loop 8 of the operating cord 9 to said plate, the latter being also equipped with arms 10 and 11 to which the drapery is adapted to be secured.

The ends of the rod 1 are telescopically received in arms 12 of end-members which are L-shaped, the other or free arm 13 of each thereof being adapted to be engaged with a wall fixture or bracket 14 secured to a window-casing or the like. The arms 12 of each of said members is of greater length than the arm 13 and either of said arms may be engaged with the rod for varying the spacing of the latter from the window-casing, said arms being otherwise identical in every particular.

Each of said arms 12 and 13 of an end-member of the structure is provided with the longitudinal slot bordered by flanges 15 and with a perforation 16 in the wall opposing said slot and in alignment with the latter. Each arm 12 and 13 is also provided with a pair of perforations 17 in its top wall and similarly in its bottom wall, said perforations being axially aligned.

The drapery carriers 3 are adapted to be attached to the cord 9 which is disposed within the rod 1. This cord must be trained over a sheave 18 disposed at one end of said rod 1 in such position as to present its groove in alignment with the hollow of said rod. The cord 9 must also be trained over two sheaves 19 and 20 at the other end of the rod 1 which are similarly positioned and the ends of the cord 9 must depend below the rod for digital engagement. The perforations 17 are provided for the passage of the depending end-portions of said cord 110

and are so spaced from the perforation or opening 16 so that when the sheaves 19 and 20 are mounted in an arm 12 or an arm 13 of an end-member of the rod, said openings 5 or perforations 17 are disposed in proper position relatively to the grooves of the sheaves 19 and 20 to permit dependence of the end portions of the cord 9 from the latter without contacting with the walls of 10 said perforations 17, the latter being of considerably greater diameter than said cord 9.

The sheave 18 is disposed between the arms of a U-shaped frame 21 and is rotatable on the smooth cylindrical head portion 15 of a set-screw 22. The latter has a threaded shank 23 of smaller diameter than said head portion and extends freely through an opening of proper diameter in one of the arms of the member of frame 21. Said threaded 20 shank engages in the threaded opening in a nut or plate 24 disposed to span the slot in the arm containing said frame 21 so as to clamp the flanges 15 bordering said slot between said nut 24 and the arm of said 25 member 21 through which said threaded shank passes, the said arm being, in turn, clamped against the annular shoulder at the base of said threaded shank.

A similar frame 25 carries the sheaves 30 19 and 20, one of the latter, preferably the larger which is disposed adjacent the middle portion of the frame 25, is rotatable on the head portion of the screw 26 which is identical with the screw 22, the smaller 35 sheave 19 being rotatable on a pin 27 permanently associated with the frame 25.

The frames 21 and 25 may be associated 40 with the arms 12 and 13 interchangeably and the end members interchanged as desired, it being necessary, of course, to train the end portions of the cord 9 over the 45 sheaves 19 and 20 according to the position of the member carrying said frame 25 in order that the said sheaves 19 and 20 may function.

In assembling the structure, the cord 9 is preferably trained over the sheave 18 before the frame 21 is inserted into the arm 12 or 13 of the end member which is to 50 contain the same. Said frame is then inserted into said arm and there secured. The free end portions of the cord 9 are then trained over the sheaves 19 and 20 before the frame 25 is inserted into the arm 12 or 55 13 of the other end member of the rod. Said free end portions of said cord are then readily passed through the desired arm of the end member and through the respective perforations 17 in the lower wall of the 60 latter and thereupon the frame 25 is inserted and secured.

The portion of the cord 9 disposed between the frames 21 and 25 is now passed through the slot in the rod 1, the several 65 sets of drapery carriers then mounted on

the latter and the end members then slipped into place. Loops 8 of oppositely traveling portions of the cord 9 within the rod 1 are then drawn through the slots 6 and over projections 7 of the respective master-carriers disposed nearest the middle of the rod, care being exercised that the said master-carriers are disposed equidistantly from the free arms of the end members of the rod and that no slack is left between the points 75 of attachment of the cord 9 to said master carriers and the sheave 18.

Weights or other means for maintaining the cord taut are usually secured to the free ends of the latter either before attachment to the master carriers or thereafter, the assembled structure being now ready for mounting on the wall fixtures or brackets 14.

In the drawings I have shown only the 85 master-carriers above referred to, it being obvious that additional carriers must be provided between each master-carrier and the frame 21 or 25, said additional carriers being unattached to the cord 9.

The relative diameters of the sheaves 19 and 20 is such that the portions of cord trained over each will be out of interfering 90 relation to each other.

The invention as illustrated and described 95 is directed to the specific type of curtain rod disclosed without, however, excluding modifications and variations of the structure of the sheave carriers and arrangement of sheaves to adapt the invention to other types 100 of curtain rods within the definition of the appended claims.

I claim as my invention:—

1. A curtain rod including hollow end members each provided with a continuous 105 slot in one wall thereof and provided with a perforation in the wall opposing said slot and in alignment with the latter, there being at least one opening in each of the remaining walls thereof having their axes 110 extending perpendicularly to that of said perforations, sheave carriers including frames snugly fitting and slideable within said end members and each thereof carrying at least one sheave, and clamping means associated with said frames and said end-members and including a member passing through said perforations for holding said frames in fixed position with the sheaves 115 thereof disposed relatively to the said openings for the passage through the latter of the end portions of a cord trained over said sheaves.

2. A curtain rod including hollow end-members each provided with a continuous slot in one wall thereof and provided with a perforation in the wall opposing said slot and in alignment with the latter, there being at least one opening in each of the remaining walls thereof having their axes 125 ex- 130

- tending perpendicularly to that of said perforation, sheave carriers including frames 5
slidable within said end-members and each thereof carrying at least one sheave, and
clamping means associated with said frames and said end-members and including a member 15
passing through said perforations for holding said frames in fixed position with the sheaves thereof disposed relatively to the said openings for the passage through the latter of the end portions of a cord trained over said sheaves.
3. A curtain rod including hollow end-members each provided with a continuous slot 20
in one wall thereof and provided with a perforation in the wall opposing said slot and in alignment with the latter, there being at least one opening in each of the remaining walls thereof having their axes extending perpendicularly to that of said perforation, sheave carriers including frames 25
slidable within said end-members and each thereof carrying at least one sheave, and clamping means associated with said frames and said end-members and including a member 30
passing through said perforations for holding said frames in fixed position with the sheaves thereof disposed relatively to the said openings for the passage through the latter of the end portions of a cord trained over said sheaves, said member constituting the shaft of a sheave.
4. A curtain rod including hollow end-members, each provided with a continuous slot 35
in one wall thereof and provided with a perforation in the wall opposing said slot and in alignment with the latter, there being at least one opening in each of the remaining walls thereof having their axes extending perpendicularly to that of said perforation, sheave carriers including frames 40
slidably within said end-members and each thereof carrying at least one sheave, and clamping means associated with said frames and said end-members and including a member 45
passing through said perforations for holding said frames in fixed position with the sheaves thereof disposed relatively to the said openings for the passage through the latter of the end portions of a cord trained over said sheaves, said member constituting the shaft of a sheave.
5. A curtain rod including hollow end-members, each provided with a continuous slot 50
in one wall thereof and provided with a perforation in the wall opposing said slot and in alignment with the latter, there being at least one opening in each of the remaining walls thereof having their axes extending perpendicularly to that of said perforation,
- sheave carriers including frames snugly fitting and slidably within said end-members and each thereof carrying at least one sheave, and clamping means associated with said frames and said end-members and including a member 55
passing through said perforations, said frame, a sheave and the slot of the end member, and a nut associated with said member and said frame for clamping the walls of the end-member bordering said slot between said nut and said frame, said openings positioned relatively to the perforations for permitting the passage of the ends of the cord trained over said sheaves.
6. A hollow curtain rod including a middle portion and two substantially L-shaped members 60
detachably associated with said middle portion, each of the arms of said end-members being provided with pairs of openings in its upper and lower walls and with an opening in a vertical wall thereof disposed in predetermined position relatively to said pairs of openings, a sheave carrier equipped with two sheaves of different diameters and adapted to be inserted into any one of the several arms of the end members with the larger sheave disposed farthest from the adjacent end of said middle portion, and means on said sheave carrier adapted to engage in said opening in a vertical wall of the arm of an end-member containing said carrier for securing the latter against movement longitudinally of said arm, the sheaves of said carrier disposed relatively to said securing means to cause the grooves 65
thereof to become so aligned with the pairs of openings in the arm containing said carrier as to permit the end portions of a cord trained over said sheaves to depend from the latter through the said pair of openings in the lower wall of said arm.
7. A sheave-carrier adapted to be mounted in a hollow curtain rod, said carrier comprising a U-shaped metal frame, at least one sheave rotatably disposed between the arms 70
of said frame, the latter provided with aligned openings of respectively different diameters, a pivot element for the sheave including a smooth cylindrical end portion of diameter to fit the larger of said openings and of a length greater than the distance between opposed faces of said arms and terminating in an annular shoulder engaging the arm containing the smaller opening, and a threaded shank passing through the latter, and means for engaging said threaded shank and a wall of the rod for securing said carrier against movement relatively to the latter.

CHARLES W. KIRSCH.
